US0D1064532S

(12) United States Design Patent (10) Patent No.: US D1,064,532 S
(45) Date of Patent: * Mar. 4, 2025

(54) SQUARE TOE SHOE WITH HEEL AND OUTSOLE PATCH

(71) Applicant: Gavrieli Brands LLC, Beverly Hills, CA (US)

(72) Inventor: Kfir Gavrieli, Beverly Hills, CA (US)

(73) Assignee: Gavrieli Brands LLC, Beverly Hills, CA (US)

() Term: 15 Years

(21) Appl. No.: 29/924,081

(22) Filed: Jan. 17, 2024

Related U.S. Application Data

(60) Continuation of application No. 29/875,607, filed on May 8, 2023, now Pat. No. Des. 1,014,025, which is a division of application No. 29/773,809, filed on Mar. 11, 2021, now Pat. No. Des. 989,455.

(57) CLAIM

The ornamental design for a square toe shoe with heel and outsole patch as shown and described.

DESCRIPTION

The broken lines illustrate features that form no part of the claimed design.

1 Claim, 7 Drawing Sheets
